Donald R. Studebaker

(21) Appl. No.: **29/321,318**

(57) **CLAIM**

(22) Filed: **Jul. 15, 2008**

The ornamental design for a headlight of motor vehicle, as shown and described.

(51) **LOC (9) Cl.** 26-06

DESCRIPTION

(52) **U.S. Cl.** **D26/28**

FIG. 1 is a perspective view of a headlight of motor vehicle;

(58) **Field of Classification Search** D26/28-36;

FIG. 2 is a front view thereof;

362/459-468, 475-478, 485-487

FIG. 3 is a left side view thereof;

See application file for complete search history.

FIG. 4 is a top view thereof;

(56) **References Cited**

FIG. 5 is a perspective view showing a cover portion is opaque;
